MERRILL W. GALLAWAY, OF NEW YORK, N. Y.

CIGARETTE HOLDER AND DELIVERER.

1,281,152.

Specification of Letters Patent.

Patented Oct. 8, 1918.

Application filed March 23, 1918. Serial No. 224,129.

To all whom it may concern:

Be it known that I, MERRILL W. GALLAWAY, a citizen of the United States, residing at New York city, N. Y., have invented certain new and useful Improvements in Cigarette Holders and Deliverers, of which the following is a clear, full, and exact description.

This invention relates to cigarette holders for delivering a cigarette, and the principal object of the invention is to provide a waterproof and sanitary inclosure for cigarettes, from which a single cigarette may be delivered without the necessity of handling it. Other objects of the invention are to provide improved ejecting means for a single cigarette, which gravitates down to the place of ejection; to provide improved means for closing the delivery opening, and to generally improve the construction of cigarette holders and deliverers in such way that the use of springs is obviated, the means for ejecting a cigarette and the means for closing the delivery opening being held by friction in the position to which they are moved during their use.

These being among the objects of the present invention, the same consists of certain features of construction and combinations of parts to be hereinafter described and then claimed with reference to the accompanying drawings illustrating one embodiment of the invention, and in which—

Figure 1 is a longitudinal sectional view of the device;

Fig. 2 is a front view thereof;

Fig. 3 is an enlarged transverse section on the line 3—3 Fig. 1, showing how the sliding closure is guided;

Fig. 4 is an enlarged section on the line 4—4 Fig. 1, viewed in the direction of the arrow and showing the construction adjacent the delivery opening;

Fig. 5 is a transverse section on the line 5—5 Fig. 1, viewed in the direction of the arrow and showing certain details of the ejecting means; and

Fig. 6 is a view similar to the lower part of Fig. 1, which latter figure shows the ejecting means retracted, while Fig. 6 shows the same in the position in which it has just delivered a cigarette, and showing how the

next cigarettes dispose themselves in the device.

Referring to the drawings, a substantially rectangular casing or box 10 is provided, said casing having flat sides. Said box is just narrow enough to conveniently receive a single row of cigarettes which are adapted to gravitate down in the casing, said casing being provided with a suitable cover 11 which is closed after the cigarettes have been placed in the casing. The said cover should fit so snugly on to the casing that a watertight joint is formed between it and the casing. The casing comprises a front wall 12, a back wall 13 and a bottom wall 14, in addition to the flat side walls between the walls 12, 13. In the lower end of the front wall 12, directly above the front end of the bottom wall 14, there is provided a delivery opening 15 of circular shape, and the bottom wall 14 is curved transversely correspondingly.

Means are provided for ejecting a single cigarette through the delivery opening 15, said ejecting means comprising, as clearly shown in Figs. 1, 5 and 6, an inner sliding plate 16 and an outer sliding plate 17 which are connected together by a connecting pin or rivet 18, which passes through and is guided in a longitudinal slot 19 in the bottom wall 14. Said sliding plates 16 and 17 are curved transversely to correspond with the transverse curvature of the bottom wall 14 of the casing, and said plates frictionally engage the said bottom wall. Inasmuch as the said plates 16, 17, are formed from springy sheet metal, it is obvious that when they are firmly connected together as by a pin or rivet 18, the springiness of the metal will tend to cause the said plates to bear upon the opposite surfaces of the bottom wall 14 on which they slide, so that a positive frictional engagement of the ejecting means with the said bottom plate is assured. Preferably, the end portions of the two sliding plates 16, 17, are substantially the same length at either side of the connecting pin 18, and the forward portions of said plates are desirably of the same length so that the breech in the bottom wall, which is formed by the slot 19, will be absolutely closed, and there is greater need for this con-

dition in advance of the said pin or rivet than back of it, although there should be an absolute closure all around the slot 19. The closure of the slot is furthermore assured 5 from the fact that the curvature of the sliding plates 16 and 17 is the same as the bottom wall 14. Preferably the length of the rear portion of the sliding plate 17 is such as to terminate a short distance away from the 10 back wall 13 of the casing when the ejecting means is retracted, with the connecting pin or rivet 18 in contact with the rear end wall of the slot 19.

The length of the advance portions of the 15 sliding plates 16, 17, being such as to absolutely close the slot when the ejecting means is retracted, the forward extremities thereof will stop just short of the delivery opening 15 and the front end of the bottom wall 20 14, when the ejecting means is moved forward until the connecting pin or rivet 18 strikes the front end of the slot 19.

The sliding plate 16 on the inside of the casing 10 is provided at its rear end with an 25 ejecting nose 20 which may be of suitable shape, but should be rounded at its upper and rear edges so as not to injure a cigarette. The bottom slide plate 17 constitutes a guard for the slot 19 and it is provided with an 30 outwardly projecting finger piece or button 21, which may be formed as an extension of the connecting pin or rivet 18. By actuating the ejecting means, the lowermost cigarette will be ejected through the delivery 35 opening 15, and when the said ejecting means is retracted, the said slot 19 will be absolutely closed against the entrance of water, so that water-tight joints are provided between the members of the ejecting 40 means and the bottom wall of the casing.

Referring more particularly to Figs. 1 and 6, the back wall 13 of the casing will be seen to be provided with an inclined or beveled shoulder 22, the inclined surface thereof 45 starting from the inner surface of the back wall and extending gently forwardly and downwardly to a point above the ejecting nose 20, and to a point behind the rear end of the lowermost cigarette. The front wall 50 12 of the casing is also provided with an inclined or beveled portion, the inclined or beveled surface of which is indicated by 23, and may be formed in any suitable manner, or as shown specifically in Fig. 1, that is 55 to say, the part or portion on which the inclined surface is provided may consist of a shoulder 24 which is provided with an upper inclined surface 25 that starts from the inner surface of the front wall and inclines 60 inwardly and downwardly so as to terminate at a point about opposite the forward end of the second cigarette from the bottom of the casing. The upper edge of the inclined or beveled surface 23 is formed on a straight

line at 26, extending from side to side of the casing at right angles to said sides, that is to say, the uppermost portions of the inclined or beveled surface 23 are not defined by a curve which would correspond to the curve of the delivery opening 15. The said 70 front inclined or beveled surface 23 therefore commences on a straight line such as at 26, and is gradually formed and merged into a curved edge of the delivery opening, as clearly indicated in Fig. 4. 75

The advantage of the said construction of the front inclined surfaces is that there will be no inside corner continuations of the lower corners of the front wall where they join the said inclined surface 23, and which 80 would be the case if the starting edge of the beveled surface was curved to correspond with the curvature of the delivery opening, and hence there is no danger of the advance end of the second cigarette in the row being caught by such a corner, and perhaps be prevented from properly gravitating to ejecting position or perhaps resulting in injury to the said cigarette. By reason of the inclined or beveled rear shoulder 22 there is 85 formed a recess 27 below the said shoulder, and this recess is preferably of such a height that the shoulder 22 cuts off or intercepts about one-third of the diameter of the rear 90 end of the lowermost cigarette. Said recess 27 is also of such size as to nicely accommodate the ejecting nose 20, as clearly 95 shown in Fig. 5.

It will be seen from Fig. 1 that the cigarettes adjust or dispose themselves in the 100 casing 10 so that the lowermost cigarette falls in position upon the curved inner surface of the ejecting slide 16. Its rear end cannot be jammed into the smaller recess 27, in which the ejecting nose 20 is retracted in 105 position to engage the said rear end of the cigarette. When it is desired to deliver a cigarette, the ejecting means is pushed forwardly, thereby projecting a cigarette, as indicated in dotted lines in Fig. 1, and the 110 corresponding position of the ejecting means is also indicated in dotted lines. When the projected cigarette has been removed, the next cigarettes will fall in substantially the 115 position shown in Fig. 6, the ejecting means being still in forward position. In falling to the position shown, the lowermost cigarette will be offset from the remainder of the cigarettes, by the action of the front and rear inclined guiding surfaces 22, 23, and 120 being so offset from the rest of the cigarettes, the lowermost cigarette is in the best position for its subsequent ejection, and will fall into the position of the lowermost cigarette shown in Fig. 1 when the ejecting 125 means has been retracted so as to position the ejecting nose in the recess 27. The advantage of the construction of the front in-

clined surface 23 will be obvious from Fig. 6, as it will be seen that such a construction will prevent the front end of the lowermost cigarette being caught on corners at the upper portion of the inclined surface.

Closure means are provided for the delivery opening 15, and the joint between the said closure means and the parts of the casing should be formed water-tight, as are the few other joints of movable parts with the casing, so as to prevent the entrance of moisture. To this end, the front wall 12 of the casing is provided with a bead 28 which projects from opposite sides of the casing and extends parallel with said casing at both sides, and at the bottom of the casing said bead is formed with a curved, unbroken continuation 29, which extends around the delivery opening 15. This bead reinforces the structure at these parts, and it is formed continuously along its inner edge with a groove 30. Said groove provides means for guiding the opposite side edges of a flat sliding closure-plate 31, the said plate having a curved lower edge 32, all of which is clear from Figs. 1, 2 and 3.

It will be seen that by reason of the described closure construction, suitable friction is provided by the ample contact surfaces between the sliding closure and the guiding surfaces, and that when the said closure is closed in the position as shown in Fig. 1, its curved lower edge 32 will be nicely received in the curved portion of the groove 30. The said closure plate or sliding closure 31 is provided with a finger piece or button 33, whereby it may be operated so as to expose the delivery opening 15, as shown in Fig. 1, or to close it as shown in Figs. 2 and 6. It will be seen that additional friction for the sliding closure is provided because the groove 30 is directly in advance of the front surface of the wall 12, so that the said sliding closure will have frictional contact not only with the walls of the groove 30 but with the front wall 12.

To prevent the withdrawal of the slide 31 from its guiding grooves when the cover 11 of the box is open, any suitable stop 36 may be provided upon the front wall 12.

It is obvious that when the parts of the device are made of sheet metal and constructed substantially as described, that the movable parts are held snugly and by friction in contact with the other parts of the casing, so that a water-tight and sanitary inclosure for the cigarettes is provided, and these advantages and other advantages of the invention will be apparent to all users of cigarettes.

Obviously the invention is susceptible of modification, and various modifications may be resorted to without departing from the spirit and scope of the claims.

What I claim as new is:—

1. In a cigarette holder and deliverer, the combination of a substantially rectangular casing having a cover joined water-tight therewith, said casing being sufficiently narrow to snugly accommodate a single row of cigarettes and having a delivery opening at the lower end of its front wall, a cigarette ejector having frictional guiding means arranged on the bottom-wall extending away from said opening and joined water-tight with said casing, and a sliding closure for said opening in tight contact with said front wall, said opening being bounded by the side and bottom walls of said casing and said walls being provided outside of said opening with a continuous sealing and guiding groove in which the sides and end of said closure are received and closely confined.

2. In a cigarette holder and deliverer, the combination of a substantially rectangular casing having a cover joined water-tight therewith, said casing being sufficiently narrow to snugly accommodate a single row of cigarettes and having a delivery opening at the lower end of its front wall, a cigarette ejector having frictional guiding means arranged on the bottom-wall extending away from said opening and joined water-tight with said casing, and a sliding closure for said opening, frictionally guided on said front wall and joined water-tight with said casing, said casing having inclined cigarette guiding surfaces on both its front and back walls, the front inclined surface merging into the upper edge of said opening and the back inclined surface terminating in a plane intersecting the upper part of said opening.

3. In a cigarette holder and deliverer, the combination of a substantially rectangular casing having a cover joined water-tight therewith, said casing being sufficiently narrow to snugly accommodate a single row of cigarettes and having a delivery opening at the lower end of its front wall, a cigarette ejector having frictional guiding means arranged on the bottom-wall extending away from said opening and joined water-tight with said casing, and a sliding closure for said opening, frictionally guided on said front wall and joined water-tight with said casing, said casing having inclined cigarette guiding surfaces on both its front and back walls, the front inclined surface merging into the upper edge of said opening and the back inclined surface terminating in a plane intersecting the upper part of said opening, the bevel of said front inclined surface commencing on a line joining it with the inner surface of said front wall and which line is perpendicular to the side wall of said casing.

4. In a cigarette holder and deliverer, the

combination of a substantially rectangular casing sufficiently narrow to snugly accommodate a single row of cigarettes and having a delivery opening at the lower end of its front wall, said casing also having inclined cigarette guiding surfaces on both its front and back walls, the front inclined surface merging into the upper edge of said opening and the back inclined surface terminating in a plane intersecting the upper part of said opening, and an ejector for the cigarettes.

5. In a cigarette holder and deliverer, the combination of a substantially rectangular casing sufficiently narrow to snugly accommodate a single row of cigarettes and having a delivery opening at the lower end of its front wall, said casing also having inclined cigarette guiding surfaces on both 15 its front and back walls, the front inclined surface merging into the upper edge of said opening and the back inclined surface terminating in a plane intersecting the upper part of said opening, and two slide plates 20 connected together and their connection extending through a longitudinal slot in the bottom wall of said casing, one of said plates being guided upon the inner surface of said bottom wall and provided with an 25 ejecting nose, and the other plate being guided on the outer surface of said bottom wall and provided with means for moving it longitudinally.

6. In a cigarette holder and deliverer, the combination of a substantially rectangular casing sufficiently narrow to snugly accommodate a single row of cigarettes and having a delivery opening at the lower end of its front wall, said casing also having inclined cigarette guiding surfaces on both 35 its front and back walls, the front inclined surface merging into the upper edge of said opening and the back inclined surface terminating in a plane intersecting the upper 40 part of said opening, the bevel of said front inclined surface commencing on a line joining it with the inner surface of said front wall and which line is perpendicular to the side walls of said casing, and the back wall 45 of said casing having a recess adjoining the bottom wall and which is of considerably less height than the diameter of said delivery opening, said back inclined surface extending to said recess, and ejecting means 50 provided with a nose movable into said recess.

7. In a cigarette holder and deliverer, a substantially rectangular casing having side walls spaced to accommodate a row of 55 cigarettes and having a transversely curved bottom wall, said casing having in its front end a delivery opening partly bounded by the side and bottom walls, said bottom wall having a longitudinal slot, two springy 60 metal slide plates respectively sprung into 65

fitting contact with the inner and outer faces of the said bottom wall, means extending through said slot for connecting and holding said plates in close frictional contact with the opposite faces of said slotted wall, 70 said plates normally sealing said slot, and an ejecting nose on said inner slide plate.

8. In a cigarette holder and deliverer, a substantially rectangular casing sufficiently narrow to snugly accommodate a single row 75 of cigarettes, said casing having a delivery opening at the lower end of its front wall and having its bottom wall transversely curved and provided with a longitudinal slot, two springy metal slide plates closely 80 sprung into fitting contact with the inner and outer curved faces of said bottom wall and connected together through said slot in close frictional contact with the said slotted wall, said plates normally covering said 85 slot, and an ejecting nose on said inner slide.

9. In a cigarette holder and deliverer, the combination of a substantially rectangular casing sufficiently narrow to snugly accommodate a single row of cigarettes, and having a delivery opening at the lower end of its front wall, a bead projecting from the front side corners and the front bottom corner of said casing, said bead being formed 90 with an inner groove directly in front of the plane of said front wall, so that said groove extends along opposite edges of said front wall and is curved around the lower part of said opening, and a sliding closure guided 100 in said groove upon said front wall, and the lower end of which is shaped to be received in the curved portion of said groove.

10. In a cigarette holder and deliverer, a casing having side walls spaced to accommodate a row of cigarettes and having a curved bottom wall, the front end wall of said casing being cut away at its lower end to form a cigarette delivery opening partly bounded by the side and bottom walls, a 110 sliding closure for said opening extending over a substantial portion of said front wall when the closure is in operative position, said side and bottom walls being provided with a continuous guiding and sealing 115 groove extending about and outside said opening, in which the side edges of said closure are closely confined and into which the end of said closure tightly fits when said closure is in closing position, the plane of 120 said groove being so located with respect to the plane of the front wall of said casing that said closure is held in tight waterproof contact with said front wall.

11. A cigarette holder and deliverer comprising, in combination, a casing having side walls spaced to accommodate a row of cigarettes and a curved bottom wall and having at the lower end of its front wall a delivery opening partly bounded by said 125 130

side and bottom walls, a sliding closure, said side and bottom walls being provided with a continuous guiding and sealing groove extending about and beyond said opening, in which the side edges of said closure are closely confined and guided and into which the end of said closure tightly fits, and said groove being outside said opening and in a

plane causing it to hold said closure in tight contact with the front wall of said casing, 10 and a cigarette ejector arranged to eject a cigarette through said opening.

Signed at New York city, N. Y. this 20th day of March 1918.

MERRILL W. GALLAWAY.

It is hereby certified that in Letters Patent No. 1,281,152, granted October 8, 1918, upon the application of Merrill W. Gallaway, of New York, N. Y., for an improvement in "Cigarette Holders and Deliverers," errors appear in the printed specification requiring correction as follows: Page 4, line 81, claim 8, strike out the words "sprung into"; same page and claim, line 80, before the word "closely" insert the words *sprung into*; and that the said Letters Patent should be read with these corrections therein that the same may conform to the record of the case in the Patent Office.

Signed and sealed this 10th day of December, A. D., 1918.

[SEAL.]

F. W. H. CLAY,

Acting Commissioner of Patents.
